MOLDING

Leo W. Potvin, Springfield, Mass.

Application April 17, 1956, Serial No. 578,742

4 Claims. (Cl. 20—74)

This invention relates to new and useful improvements in devices for connecting or receiving and concealing the adjacent edges of angularly disposed cove members.

Cove members of relatively thin and rigid material are used for many purposes. As one example, the lower horizontal portion of a cove is disposed on a floor and curves upwardly over the jointure of the floor and adjacent wall to a vertical wall portion. As another example, the horizontal cove portion may be disposed on the upper side of the horizontal surface of kitchen equipment with the vertical portion of the cove disposed against an adjacent vertical wall or the like.

Coves having the curve connected horizontal and vertical portions are used in many locations to conceal the angular jointure of angularly related surfaces and for other purposes.

Difficulty has been experienced in concealing or connecting the adjacent sections of cove material as in a corner where the vertical walls or the like are angularly related, commonly at right angles.

In a corner, the adjacent edges of adjacent cove sections extend vertically downwardly, then curve outwardly and downwardly and horizontally so as to bisect the angle between the vertical portions.

Separate lengths of strip material have been used for the vertical and horizontal edges of the cove sections with another section of material for the curving zone of the edges. The results have been more or less makeshift with an undesirable appearance.

According to the novel features of this invention a single or continuous member is provided for the adjacent edges of adjacent cove sections in a corner and is formed to receive the edges throughout the vertical, curved and horizontal portions of said edges.

The novel features of the invention in the present preferred form thereof will be described in connection with the accompanying drawings wherein:

Fig. 1 is a front elevational view of a device embodying the novel features of the invention adjacent edges of cove sections;

Fig. 2 is a side elevational view of the device shown in Fig. 1;

Fig. 3 is a plan view of the upper end of the device shown in Fig. 1;

Fig. 4 is a perspective view of angularly arranged cove sections;

Fig. 5 is a plan view of cove sections having the device of the invention associated therewith; and

Fig. 6 is a sectional view on line 6—6 of Fig. 5.

Referring now to the drawings more in detail the novel features of the invention will be described.

The connecting device of the invention is represented by 2 and consists of an elongated strip or body of any suitable material such as aluminum or the like.

Said body has an elongated outer element 4 and an inner element 6 which may be narrower than said outer element. The elements 4 and 6 are connected by an

2

elongated web or rib 8 in such a way as to provide a space therebetween.

Side edges or flanges 4' and 6' of the elements form channels 9 therebetween which open along the opposite sides of the body for receiving adjacent edges of adjacent cove sections.

By reference to Fig. 4 for illustrative purposes cove sections 10 have vertical and horizontal portions 12 and 14 which are connected by curving portions 15. The angle between the vertical portions of the cove sections is 90 degrees, in the illustration.

The body 2 is curved intermediate its opposite ends, as at c to agree with the curvature c' of the edges of the cove sections to provide vertical and horizontal leg portions 12' and 14'.

The elements 4 and 6 of the horizontal leg portion 14' of the device are coplanar, as shown, to agree with the horizontal portions 14 of the cove sections 10.

The side flanges 4' and 6' of the vertical leg portion 12' of the device are disposed relatively angularly to agree with the angular relation of the vertical portions 12 of the coves, as shown in Figs. 3 and 5.

The flanges 4' and 6' of the vertical leg of the device and said flanges of the horizontal leg of said device merge through the curving zone c of the device.

That is the angularly disposed side flanges in the vertical leg 12' of the device as they extend through the curved zone c gradually assume a coplanar relation into the horizontal leg portion 14'.

Thus the device receives and connects the adjacent edges of adjacent cove sections throughout the vertical, curving and horizontal portions of said edges.

The device snugly receives the adjacent edges of adjacent cove section whereby to hold the sections in place.

35 The device may be secured in place by brads, screws or whatever means may be desired.

It will be noted that the body or strip is so formed that the side flanges are shaped to provide channels for receiving the adjacent vertical, curving and horizontal edges of cove sections which are disposed angularly as in a corner.

40 The body or strip may be made in any length desired and the side flanges of the vertical leg may be relatively disposed to agree with any angular relation of the vertical portions of the cove sections. The curving zone of the strip may be made to conform with any curvature such as c' of the cove sections which results from the relative angle of the vertical portions of the cove sections and the curve 15 thereof.

45 While the cove joiner is shown for the adjacent edges of cove members inside of a vertical corner it is adapted for use with cove members at the outside of a vertical corner. In either case the portions 4' and 6' of the vertical leg of the cove joiner will be angularly disposed and gradually flatten out through the curving zone.

50 Having described the invention in the form at present preferred I desire to claim and secure by Letters Patent of the United States the following:

1. A molding for connecting adjacent mitered edges of cove sections having vertical and horizontal portions connected by curved portions with the vertical portions disposed angularly comprising, a body having an elongated relatively thin rear element and an elongated relatively thin forward element of relatively less transverse width than said rear element and spaced forwardly thereof and connected thereto by a longitudinally extending rib of relatively narrow transverse width disposed intermediate midway between opposite side edges of said elements forming therewith channels open along opposite longitudinal sides of the body for receiving adjacent edges of adjacent cove sections, said body having an upper vertical portion and an intermediate portion curv-

ing outwardly and forwardly from the lower end thereof and a horizontal portion extending forwardly from said intermediate portion, opposite longitudinal side portions of said rear and forward elements of the upper portion of the body being relatively angularly disposed, said side portions of the elements of the horizontal portion of the body being coplanar, and the side portions of the elements of the intermediate portion of the body decreasing in angularity from the side portions of the upper portion of the body and merging into the coplanar relationship thereof of the side portions of the lower portion of the body.

2. A molding for adjacent mitered complementary edges of cove sections each having upper vertical and lower forward horizontal coplanar portions connected by intermediate portions of a certain curvature and being relatively disposed with said vertical portions at a ninety degree angle and the horizontal portions in coplanar relationship and the edges of the intermediate portions having a relatively different curvature comprising, a unitary elongated body having a longitudinally extending relatively thin outer element and a longitudinally extending relatively thin inner element of relatively less transverse width than said outer element connected thereto in spaced relation intermediate opposite longitudinal edges of said elements by a longitudinally extending relatively narrow rib forming with said elements a pair of channels open along opposite longitudinal sides of the body for receiving adjacent end edges of adjacent cove sections, said body having upper vertical and a lower forward horizontal portion connected by an intermediate downwardly and forwardly extending curving portion, opposite longitudinal sides of the outer and inner elements of the upper portion of the body being angularly disposed to agree with the certain angular relation of the upper vertical portions of the cove sections, opposite longitudinal sides of the elements of the curving intermediate body portion from the upper portion of the body gradually decreasing in angularity to agree with the edges of different curvature of the intermediate portions of cove sections, and lower opposite longitudinal sides of the elements in the lower portion of the body disposed in coplanar relation to agree with the planes of the horizontal portions of the cove section members.

3. A molding for connecting adjacent mitered edges of cove sections having vertical and horizontal portions connected by curved portions comprising, a body having an elongated rear element and an elongated forward element of relatively less transverse width than said rear element and spaced forwardly thereof and connected thereto by a longitudinally extending rib of relatively narrow transverse width disposed intermediate opposite side edges of said rear and forward elements forming therewith a pair of open channels on opposite longitudinal sides of said body for receiving adjacent edges of adjacent cove sections, said body having an upper vertical portion and an intermediate portion curving outwardly and forwardly from the lower end thereof and a horizontal portion

extending forwardly from the intermediate portion, opposite longitudinal side portions of said rear and forward elements of the upper portion of said body being relatively angularly disposed, opposite longitudinal side portions of said rear and forward elements of the horizontal portion of said body being coplanar, and the opposite side portions of said rear and forward elements of the intermediate portion of said body decreasing in angularity from the side portions of the upper portion of said body and merging into the coplanar relationship thereof of the side portions of the lower portion of said body.

4. A molding for adjacent mitered complementary edges of a pair of cove sections having upper vertical and lower horizontal coplanar portions connected by intermediate portions of a certain curvature and being relatively disposed with the vertical portions at a ninety degree angle to each other and the horizontal portions in coplanar relationship and with the edges of the intermediate portions merging into the adjacent vertical and horizontal portions comprising, a unitary elongated body having a longitudinally extending relatively thin outer element and a longitudinally extending relatively thin inner element of relatively less transverse width and connected thereto in spaced relation intermediate the opposite longitudinal edges of said outer and inner elements by a longitudinally extending narrow rib forming with said outer and inner elements a pair of open channels on opposite longitudinal sides of said body for receiving the end edges of adjacent cove sections, said body having an upper vertical portion and a lower horizontal portion connected by an intermediate curving portion, opposite sides of said outer and inner elements of the upper portion of said body being angularly disposed to agree with the certain angular relation of the upper vertical portions of the cove sections, opposite sides of said outer and inner elements of the curving intermediate body portion from the upper portion of said body gradually decreasing in angularity to agree with the edges of the intermediate portions of the cove sections, and opposite sides of said outer and inner elements of the lower portion of said body disposed in coplanar relation to agree with the planes of the horizontal portions of the cove sections.
